CLAIM

The ornamental design for a rear upper bumper, as shown and described.

DESCRIPTION

FIG. 1 is a front elevational view of a rear upper bumper showing our new design.

FIG. 2 is a rear elevational view thereof.

FIG. 3 is a left side view thereof.

FIG. 4 is a right side view thereof.

FIG. 5 is a top view thereof.

FIG. 6 is a bottom view thereof.

FIG. 7 is a perspective view thereof; and,

FIG. 8 is an another perspective view thereof.

1 Claim, 4 Drawing Sheets
